CLAIM

(**) Term: **14 Years**

DESCRIPTION

(21) Appl. No.: **29/154,328**

(22) Filed: **Jan. 22, 2002**

(51) LOC (7) Cl. **26-99**

FIG. 1 is a perspective view of a cable suspension assembly for a luminaire showing our design;

(52) U.S. Cl. **D26/138**

FIG. 2 is a side elevational view thereof, where the opposite side elevational view is a mirror image of this view, and, therefore, has been omitted;

(58) Field of Search D26/113, 118,

FIG. 3 is a front elevational view thereof, where the rear elevational view is a mirror image of this view and, therefore, has been omitted; and,

D26/138, 72, 85, 90; 362/220, 225, 217, 269, 277, 282, 404, 408, 147

FIG. 4 is a bottom plan view thereof.

(56) **References Cited**

The broken line showing of environmental structure is for illustrative purposes only and forms no part of the claimed design.
